Herbert S. Fairbanks

ATTORNEYS.

UNITED STATES PATENT OFFICE

REGINALD F. SEDGLEY, OF PHILADELPHIA, PENNSYLVANIA

FIREARM

Application filed April 13, 1929. Serial No. 354,833.

The object of this invention is to devise a novel fire arm which can be used with different types of shells such as for example, shells or cartridges containing gas, shot or bullets, thereby adapting it to be used as an offensive weapon or as a signal.

A further object is to devise a novel double acting firearm having novel releasing mechanism, and having a hinged barrel carrying member with which the barrel carrying member when in closed position will register with interlocking means on the stock of the firearm.

With the above and other objects in view 15 as will hereinafter appear my invention comprehends a novel firearm.

It further comprehends a novel firearm wherein the barrel is readily detachable and is carried by a carrying member which 20 causes it to register with novel interlocking means.

It further comprehends novel releasing means for the firing pin.

Other novel features of construction and 25 advantage will hereinafter more clearly appear in the detailed description and the appended claims.

For the purpose of illustrating the invention, I have shown in the accompanying 30 drawings typical embodiments of it, which, in practice, will give reliable and satisfactory results. It is, however, to be understood that these embodiments are typical only and that the various instrumentalities 35 of which my invention consists can be variously arranged and organized, and the invention is not limited to the precise arrangement and organization of these instrumentalities as herein set forth.

40 Figure 1 is a side elevation of a firearm embodying my invention.

Figure 2 is a side elevation of separate parts showing more clearly certain features 45 of the construction.

Figure 3 is a plan view of a barrel lock, in detached position.

Figure 4 is a section on line 4—4 of Figure 5.

50 Figure 5 is a sectional view showing the

firing mechanism and the manner in which the barrel is carried.

Figure 6 is an end elevation of the barrel and its carrier.

Figure 7 is a bottom plan view of a portion of the firing pin casing.

Figure 8 is a sectional view of firing pin controlling mechanism which may be employed.

Figure 9 is a section view of another form 60 of controlling mechanism for the firing pin.

Figure 10 is a sectional elevation of another embodiment for controlling the firing pin.

Similar numerals of reference indicate 65 corresponding parts.

Referring to the drawings:—

In a co-pending application for a combined club and firearm, Serial No. 322,204, I have described and broadly claimed a novel 70 construction of a double acting firing mechanism which is similar in some respects to that shown in this application.

1 designates the stock of the firearm which is provided at its rear end with a depending 75 or offset grasping portion 2. The stock is chambered as at 3 to receive the firing mechanism which includes a firing pin casing 4 within which is a firing pin 5. 6 is a firing pin spring interposed between a closure nut 80 7, in threaded engagement with the firing pin casing, and a shoulder 8 on the firing pin. The firing pin 5 is cut away to form a shoulder 9 and its forward end is reduced at 10, which, if desired, may be encircled by a re- 85 tracting spring 11. The stock has secured to it a breech 12 in the form of a ring having a diaphragm 13 provided with an aperture 14 through which is adapted to pass the striking end of the firing pin 5. This barrel 12 is se- 90 cured to the stock in any desired manner, and, as illustrated, in Figure 5 the stock is re-cessed to receive the rearwardly extending annular flange of such breech.

The stock is recessed to receive a block 15 95 to which the firing pin casing 4 is fixed in any desired or conventional manner so that it is accurately positioned within the stock. The stock is recessed as at 16 to receive the trigger 17 which latter has connected to it a sleeve 100

18 which is provided with a slot 19 which extends through the sleeve and into a portion of the trigger 17 so that it is adapted to receive a firing pin actuating member 20 which normally tends to move upwardly due to the provision of a spring 21. The sleeve 18 is slidably mounted on the firing pin casing 4. The breech 12 is provided with circumferentially spaced lugs 22 forming circumferentially spaced recesses 23.

10 The breech 12 has hinged to it at 24 a ring 25 which is provided with circumferentially spaced ribs 26.

27 designates the barrel which is provided with the circumferentially spaced ribs 28 each of which is provided with a recess 29 in its periphery into which is adapted to extend a locking plunger 30 and a locking member 31 which extends into a recess 32 in the breech 12 and which is normally retained in its forward or locking position by means of a spring 33. The locking member 31 is provided with a contact portion 34 which preferably has its outer face inclined forwardly.

25 The firing pin casing 6 is cut away as at 35 on its bottom face and terminates in the cam portions 36. The trigger member 20, as shown in Figures 5 and 8, is rectangular in cross section and the slot 19 is also rectangular to receive such trigger member while in Figure 9 and aperture 37 is provided to receive a cylindrical plunger 38 which is moved outwardly by means of the spring 39. In Figure 10 instead of using the trigger member such as 20 or 38, a spring 40 is employed and the sleeve is cut away to permit such spring to move inwardly, and the trigger 41 is pivotally carried by the sleeve instead of being fixed thereto as in the other figures as shown. A trigger retracting spring 42 cooperates with the sleeve 18 to effect the forward movement of the trigger and retain it in its forward position.

It will now be apparent that, assuming the parts are in the position seen in Figure 5 and the barrel and its carrier 25 are swung upwardly, the barrel 27 will be in alignment with the breech 12 so that when it is moved rearwardly it will pass into the breech 12, the lugs 28 passing through the recess 23 and the barrel 27 can then be turned in a counter-clockwise direction until the locking pin 30 engages a recess 29 whereupon the barrel will be locked in accurate alignment.

65 Assuming now that the firearm is loaded, the cartridge or shell being contained within the barrel 27 in the usual manner, the user draws rearwardly the trigger 17 which causes the trigger member 20 to engage the shoulder 9 and move the firing pin 5 rearwardly. During this rearward movement the trigger member 20 rides on the walls of the cut away portion 35 and as it comes into contact with the cam portions 36 the trigger member 20 is moved downwardly

against the pressure of the spring 21 until it is released from the shoulder 9 whereupon the firing pin spring 6 which has been compressed causes the firing pin 5 to move forwardly to effect the firing of the cartridge. 70

When it is desired to remove the cartridge or shell which has been fired, the user places his thumb or finger on the contact portion 34 of the locking member 31 and draws it rearwardly, thereby causing the locking pin 30 to become disengaged from the recess 29 in the barrel 27 whereupon by a clockwise movement of the barrel 27 and the upward longitudinal movement, the barrel will move into the ring 25 to interlock therewith and the barrel can be swung into the position seen in Figure 5 ready for the removal of the exploded shell or cartridge.

20 In some cases arising in practice it is not necessary to have the barrel carrier and aligning member 25 as the firearm will operate in the same way and in some cases this can be dispensed with. It is, however, a distinct advantage in having the barrel carrier 25 hinged to the breech since it enables one 90 to hold the firearm in one hand while reloading. If the barrel carrier 25 is not employed it will be apparent that the barrel is inserted into the breech by a longitudinal movement and then partially rotated to engage the 95 locking mechanism.

25 It will be apparent that any desired or conventional type of cartridge can be employed in the barrel and a sub-gauge barrel may be inserted in the barrel 27 if desired to 100 adapt it for different types of shells or cartridges.

30 It will now be apparent that I have devised a new and useful firearm which embodies the features of advantage enumerated as desirable in the statement of the invention and the above description, and while I have, in the present instance, shown and described preferred embodiments thereof which will give in practice satisfactory and reliable results, 110 it is to be understood that these embodiments are susceptible of modification in various particulars without departing from the spirit or scope of the invention or sacrificing any of its advantages.

35 Having thus described my invention what I claim as new and desire to secure by Letters Patent, is:—

1. In a firearm, a stock, a breech on the stock, a barrel carrier hinged to the breech, 120 a barrel adapted to be received in and interlocked with said barrel carrier, and a locking member longitudinally slidably in said breech to interlock with said barrel and retain it in aligned position with respect to 125 said breech.

2. In a firearm, a stock, a breech thereon, a barrel carrier hinged to said breech, a barrel extending through said barrel carrier and interlocked therewith, said breech having reg- 130

istering means with said barrel when it is in closed position, and a spring pressed locking member adapted to lock with the barrel when the barrel is moved rearwardly into the breech and partially rotated therein.

5 3. In a firearm, a stock, a breech fixed thereto, a barrel carrier hinged to said breech, said breech and barrel carrier having registering lugs and recesses when the carrier is in closed position, a barrel having lugs and recesses to interlock with the lugs and recesses of said breech and having locking recesses in its inner end, and a manually released spring pressed plunger carried by said 10 stock and adapted to interlock with a locking recess of said barrel when said barrel is moved rearwardly into said breech and partially rotated therein.

15 4. In a firearm, a firing movement comprising a firing pin having a shoulder, a firing pin spring to effect the advance of said firing pin, a firing pin casing having a slot, the walls of which form a cam, a trigger slidable on said firing pin casing, a spring tending to 20 retain said trigger in its forward position and a spring pressed trigger member carried by said trigger and extending through said slot to engage the firing pin.

25 5. In a firearm, a firing movement comprising a firing pin casing having a slot, the wall of which forms a cam, a firing pin provided with a shoulder and mounted within said casing, a firing pin spring to advance said firing pin, a trigger mechanism comprising a sleeve 30 slidable on said firing pin casing and provided with an opening through it, a spring tending to retain said trigger mechanism in its forward position, a grasping portion having an opening to register with the opening in 35 said sleeve, and a spring pressed trigger member insertable through the opening in said sleeve into the opening in said grasping portion, and adapted to engage said shoulder of the firing pin to retract said firing pin and 40 to release said firing pin on engagement with said cam.

45 6. In a firearm, a trigger mechanism comprising a sleeve, a spring tending to retain said trigger mechanism in its forward position, a grasping portion connected with said sleeve, an opening through said sleeve and into said grasping portion, a spring in said opening, and a trigger member insertable into 50 said opening into contact with said spring.

55 7. In a firearm, a stock, a breech thereon, a barrel, said barrel and breech having complementary lugs and recesses to align it whereby the barrel can be inserted by relative longitudinal and rotary movement of the 60 barrel and breech, and a manually actuated spring pressed locking member carried by said breech to lock said barrel with said breech.
